UNITED STATES PATENT OFFICE

ARTHUR McDougall DUCKHAM, OF LONDON, ENGLAND.

PLANT FOR GASIFYING FUEL.

Application filed May 2, 1921. Serial No. 466,222.

To all whom it may concern:

Be it known that I, ARTHUR McDougall DUCKHAM, a subject of the King of Great Britain, residing in London, England, have invented a new and useful Improvement in Plants for Gasifying Fuel, of which the following is a specification.

In a plant for the total gasification of coal or other carbonaceous matter in which one portion of the plant consists of one or more retorts or chambers for the carbonization of the material and the other and usually lower portion consists of a generator for the manufacture of water gas, difficulty is occasioned by the various differing pressures which occur within the plant during the periods of blow and run in the manufacture of the water gas. It is usually desired that the products of combustion from the blow period shall not ascend the retorts or chambers and so contaminate the gas made in the carbonizing process, but shall pass from the generator to external flues surrounding the retorts or chambers and heat the latter. By the present invention the necessity of any valve on the gas outlet of the retorts or chambers which has to be operated at each period of blow or run is avoided.

For this purpose the outlet pipe from the retort or chamber is hydraulically sealed, and the depth of the seal is made to depend on the pressure of gas at the upper portion of the generator. By this means, should the pressure of the gas at the upper portion of the generator increase, the level of the water in that portion of the pot *c* which seals the take-off pipe *a* of the retort will be caused to rise, and consequently the discharge of gas from the upper portion of the retort will not occur until the pressure of the said gas has risen by a corresponding amount. The difference between the pressures at the upper portion of the generator and at the upper portion of the retort thus remains substantially the same.

The accompanying drawing is a vertical section through a retort and generator provided with a device constructed for the purpose in question.

The off-take pipe *a* of the carbonizing retort *b* is water sealed in vessel or pot *c*, the lid of which has a depending partition *d* dividing the pot into two equal compartments. The volatile products escaping from the retort pass away from the left hand compartment by pipe *e*, while the right hand compartment is connected, above the water level, by pipe *f* with the upper portion of the water gas generator *g*.

Coal or other carbonaceous material is fed into the retort *b* by means of a charging device *h*. Air for the "blow" period is admitted by means of the pipe *k*, and steam for the "run" period is admitted by means of the pipe *m*. During the blow period the gaseous products from the generator *g* are conveyed through channels *n'* by the pipe *n* to heating flues *o* by way of the flue *p*, secondary air being admitted by flues *q*, and the waste gases pass out by way of the pipe *r*.

The gas pressure in the right hand compartment of the pot *c* varies with that in the upper portion of the generator, wherefore the level of the water in the left hand compartment similarly varies and the relationship between the pressure at the upper portion of the retort and that at the upper portion of the generator remains substantially constant.

I claim:

1. A gas plant for the total gasification of fuel, comprising a retort for the carbonization of fuel, a gas generator into which the carbonized fuel is directly discharged, a vessel containing two columns of liquid normally in equilibrium, a delivery pipe having one end opening into the upper portion of said retort and having its other end extending into and sealed by one of said columns of liquid to cause the volatile products of the carbonization to pass through said column of liquid and to escape from the surface of the latter, and a duct for transmitting elastic fluid pressure from the upper portion of the generator to the surface of the other column of liquid.

2. In a gas plant for the total gasification of fuel including a carbonizing retort and a gas generator, of the kind herein referred to, a water seal pot divided into equal compartments having free communication for passage of water between them, the outlet pipe of the retort being sealed in one compartment from which the volatile products escape, and a communicating conduit between the other compartment, above the water level, and the top of the generator.

In testimony whereof I have signed my name to this specification.

ARTHUR McDougall DUCKHAM.
